UNITED STATES PATENT OFFICE.

FREDERICK H. ALLING, OF NEW HAVEN, CONNECTICUT, ASSIGNOR TO POLLARD-ALLING MANUFACTURING COMPANY, OF NEW YORK, N. Y., A CORPORATION OF NEW YORK.

CLUTCH FOR RELIEFGRAPHS.

No. 875,679.

Specification of Letters Patent.

Patented Jan. 7, 1908.

Application filed October 6, 1906. Serial No. 337,667.

To all whom it may concern:

Be it known that I, FREDERICK H. ALLING, a citizen of the United States, residing in New Haven, in the county of New Haven and State of Connecticut, have invented certain new and useful Improvements in Clutches for Reliefgraphs, of which the following is a specification.

This invention pertains to clutch mechanism where it is necessary to cause a constantly rotating member to engage another rotatable member and cause them to rotate in unison for one revolution, and thereupon to automatically disengage, notwithstanding the fact that the operative member that caused the engagement of the members, is not retracted upon the completion of the revolution.

The mechanism is especially designed for use in the machine for producing printing surfaces, such as patented to W. E. Crane, May 11th, 1897, Number 582,177. In such machine, there are a series of coöperating die members, and means for causing the approach and recession of such members when positioned to print a certain character; which movement of the dies is operated by a revolution of a rotary member. This rotary member is actuated from a constantly rotating member, by means of clutch mechanism, which mechanism is actuated from the means used to position the mating dies.

One of the objects of the present invention is to produce a form of clutch mechanism that will cause but a single reciprocation of the die members, and hence but a single revolution of the rotary driving member therefor.

In the accompanying drawings is shown one embodiment of my invention, and certain portions of a machine for producing printing surfaces, similar to that set forth in said patent to Crane.

Figure 1 is a side elevation of such mechanism, certain parts being shown in section. Fig. 2 is an end view of one of the clutch members. Fig. 3 is a section through the clutch member on the line 3—3 indicated in Fig. 2. Fig. 4 is a section through certain parts of the clutch member shown in Fig. 2, taken on the line 4—4 indicated therein. Fig. 5 is a view similar to Fig. 4 showing the parts in different positions. Fig. 6 is an end elevation of the parts shown in Figs. 4 and 5. Fig. 7 is a separate view of the trip lever.

Fig. 8 is a view of the arm carrying the trip lever. Fig. 9 is a separate view of the cam lever for shifting the locking pawl. Fig. 10 is an end view of the spring clutch member. Fig. 11 is a side elevation of the complete machine, showing the means for operating the printing means, actuated by the eccentrics; and Figs. 12 and 13 show the sleeves having inclined surfaces for operating one clutch member.

In the mechanism shown in Fig. 1, the key levers K, corresponding to characters on the type wheels that are mounted on shafts A and B, when shifted, serve to stop constantly rotating type wheels (not shown) with the desired characters opposite. The shafts A and B are connected for rotation in unison by equal gears a and b. The shaft A carrying the gear a is rotated by a shaft member 9 carrying a friction clutch member 10.

The clutch member engages with a clutch rim 11 of a clutch member denoted generally by 12, and which is constantly rotated by any suitable means, such as a belt 8. On the shaft A, is an arm 13 carrying a lug 14. In the path of movement of the lug 14, are a circular series of stop pins 15 carried by supporting plates 16 and 17, being endwise movable therein, and connected with the levers K, whereby the depression of a key lever will shift the stop pin connected therewith, moving its extremity into the path of movement of the lug 14. The movement of the stop arm 13 is thereby arrested, and the shafts A and B are stopped, positioning the die wheels with the character corresponding to the key lever in printing position. The described arrangement of key levers, stop pins, geared printing members, and the stop arm coöperating with the stop pins, is similar to that shown in the said patent to Crane.

Upon the arresting of the shafts A and B of the printing members, means are shown in Fig. 11 for bringing them together, which are operated by connecting rods reciprocated by wrist pins on the driving shaft. In the present invention, the said means are constituted by wrist pins 18 and 19 that are connected with the clutch member 12 constantly driven from the belt 8.

In the Crane patent, a friction clutch device is used for normally rotating the printing members, whereby, upon the members being arrested through the key levers and stops, the driving member of the clutch will

110

continue its rotation, and immediately upon the printing member being released from the stop mechanism, its rotation will continue, for the purpose of permitting arrest of the printing members in different positions. In the present invention, the clutch member 10 secured to the shaft member 9 is composed of a cross arm 21 of resilient material, carrying diametrically opposite friction blocks 22 that are pressed tightly against the friction rim 11. By this means, the shaft 9 is normally rotated from the clutch member 12, but upon arrest of the printing member shafts A and B by means of the stop arm 13, the clutch arm 21 will be arrested, and the clutch blocks will slip on the rim 11 until the release of the printing members, when the clutch members will at once grip and rotate the shaft 9.

The wrist pins 18 and 19 are not rigidly secured to the clutch member 12, but are normally loose therefrom, and a pawl and ratchet mechanism is provided for connecting these members upon the pawl being shifted by the operation of mechanism controlled by the arrest of the shaft A. The wrist pins are secured to a shaft 23 that is rotatable in a sleeve bearing member 24 projecting from an upright 25. The sleeve 24 forms a journal on which rotates the clutch member 12, a friction sleeve 26 being preferably fast on the sleeve 24. A retaining plate 27 is threaded on the reduced end 28 of the sleeve 24 and engages a shoulder portion 29 on the recessed face of the clutch member. The clutch member 12 is provided with ratchet teeth 30 on the internal face 31, which teeth are engaged by a pawl 32 pivoted on an arm 33 that is fast on the extremity of the wrist pin shaft 23. The pawl is normally retained out of engagement with the ratchet wheel or clutch member 12, but upon engaging the same, the rotation of the clutch member 12 will carry the wrist pin shaft around and cause actuation of the printing members.

Means are provided for shifting the pawl into engaging position upon the arrest of the shaft member 9, and when the wrist pin shaft has made a complete revolution, the pawl is thrown out of engagement with the ratchet wheel. A cam lever 34 in the shape of a ring, as shown separately in Fig. 9, is pivoted on the plate 27, that is stationary on the bearing sleeve 24. This ring has a raised edge or peripheral portion 35, that normally engages the tail of the pawl 32, and holds its opposite end out of engagement with the ratchet wheel. The other edge portions of the cam ring are of less distance from the axis of the shaft 23. The cam ring can be rocked on its axis 36, and when moved inward, its engaging portion 35 will no longer support the tail of the ratchet 32, as shown in Fig. 5. This will permit a suitable spring to throw the ratchet outward to engage the ratchet wheel. The constantly rotating ratchet wheel will

thereby carry the arm 33 and shaft 23 around. But the cam ring is normally pressed outward and retained in the position shown in Fig. 4, by means of a plate spring 37 fast on the stop plate 27. As soon as the pawl passes the engaging portion 35 of greatest diameter of the ring 34, the cam ring will be moved outward to its former position by the spring 37; which movement is limited by means of a screw 38 fast on the cam ring and 75 having a nut 39 engaging the stop plate 27. Upon the pawl approaching the end of a revolution, its tail will engage a cam or inclined portion 40 that terminates in the said elevated edge portion 35; and the cam being returned to normal position, the pawl end will ride up this incline to the edge portion 35, and thereby be swung out of engagement with the ratchet wheel.

The cam ring 34 is depressed by means of 85 a trip lever 41 on the arm 33. The arm 33 has a slotted portion 42 in which is pivotally mounted a block 43. The lever 41 is pivoted on this block and therefore has a swinging movement on the lever in the two directions 90 at right angles. The lever 41 carries a trip pin 44 having a beveled extremity 45, that in the normal position of the lever is in engagement with the face of cam ring 34, at a place 47 as shown in Fig. 4. When the lever 41 is 95 in this position, and is moved inward, it will swing the cam lever and release the pawl, permitting the latter to engage the ratchet wheel. Should the lever 41 be held depressed, it would follow the cam ring around 100 engaging therewith until it reaches the hinged portion of the ring, the cam ring being now returned to its normal position by its spring. But after passing the hinge portion, the pin will move inside the ring because its 105 internal diameter is here enlarged beyond the radial distance of the trip pin from the axis, at 46. The pin will thereupon ride inside of the cam ring at its enlarged portion. The stop pin is normally located opposite the 110 portion 47 of the cam ring, where the internal radius is less than at the portion 46. This portion 47 is opposite the engaging portion 35 of the ring. Hence the inner face of the ring that engages the trip pin when in the 115 depressed position must have an inwardly inclined portion 48 and the stop pin will be thereby moved radially inward at this portion. This is permitted by reason of the stop pin having a swinging movement on its 120 supporting block 43. Should the trip lever be pressed inward and not released at the completion of a revolution, the stop pin will ride inside the cam ring and remain in such position without again depressing the cam 125 ring permitting the disengagement of the pawl with the ratchet wheel by the incline 40. If the stop lever were released immediately upon disengaging the tail of the ratchet from the cam lever, as soon as the pawl ap- 130

proached the completion of its revolution, the stop pin would return to this normal engaging position ready for again tripping the cam lever to disengage the pawl. But if the 5 trip lever be held in its inward position, it will be moved centrally inward by the engagement of the internal face of the cam lever at 46 and cannot engage the cam lever at the completion of the revolution to move 10 it out of position to swing the pawl out of engaging position. A spring 50 is arranged between the pawl 32 and the lever 41, which tends to swing the pawl outwardly into engagement with the ratchet wheel, and also 15 tends to swing the lever 41 to move its stop pin away from the clutch axis. This spring will cause the pawl to engage the ratchet wheel as soon as it is released from the cam ring. The spring will also swing the trip 20 lever to move its stop pin outwardly as soon as it is released after having moved inward from engagement with the inner face of the cam ring. The trip lever 41 is moved outwardly from the face of the carrying arm 33 25 by means of a plate spring 51 and its movement is limited by a stop 52, in both directions from the actions of said springs.

The trip lever 41 is actuated at each arrest 30 of the printing members by the key lever stops, through a longitudinal movement given to the clutch member 10. In the present construction, this is accomplished by having the shaft member 9 formed in two parts, comprising a sleeve 55 that is secured 35 to the spring piece 21 of the clutch member, and surrounds the extension 56 of the shaft A. The sleeve 55 has one or a pair of notches, one of which is shown in Figs. 1, 12 and 13. The notch has an incline surface 57. 40 A sleeve 58 has a correspondingly inclined portion 59. A coil spring 60 on the shaft 56 has its extremities secured to the shaft and the sleeve respectively. The spring is arranged to normally press the sleeve 55 45 against the sleeve 58 by its expansive tendency, and by its torsional construction it will tend to hold the two sleeves in the rotative position relatively in which shown in Fig. 1. But upon arrest of the sleeve 58 by reason of stop arm 13 engaging a stop pin 15, the continued rotation of clutch member 10 50 would tend to rotate the sleeve 55 on the shaft 56, and hence rotate it relative to sleeve 58.

55 The engagement of the inclined faces 57 and 59 will cause an endwise advancement of the sleeve 55, advancing the clutch arm 21 to engage the trip pin 44 and operate the clutch member as hereinbefore set forth; 60 causing rotation of the wrist pins for one revolution only. This rotation of sleeve 55 will be arrested by reason of stop portion 61 coming into engagement with a stop portion 62 on the inclined face 59. Thereupon further 65 rotation of the sleeve 55 is prevented, the

clutch member 10 sliding on its engaging face of the clutch member 11. But upon release of the stop arm 13, the sleeve 58 will be free to rotate, and will be carried around with the sleeve 55 by reason of the frictional engagement between the clutch members. As soon as the sleeve 58 is free to rotate, the spring 60 will tend to untwist and advance the sleeve 58, because the spring was put under torsional strain when the sleeve 55 advanced 70 upon arrest of the sleeve 58. This will advance the sleeve 58 to the position indicated in Fig. 13, in which the sleeves are in the same rotative position on the shaft, but the sleeve 55 has not been shifted axially upon 75 the shaft to return it to its former position as shown in Fig. 1. Any compression that is put upon the spring 60 during the advancement of the sleeve 55 would tend to react and cause this axial movement. But this might 80 be prevented by friction on the sleeve. To insure the return of the sleeve 55 to its former position, the notch in the sleeve 55 is provided with another inclined face 86; and the sleeve 58 is provided with a similar inclined face 87. In the position in which the sleeves are shown in Fig. 13, the advance of the sleeve 58 by the torsional action of spring 60 will bring these inclined faces into engagement and it will be understood that this torsional action of the spring or reaction, will 85 cause the engagement of these inclined faces to draw the sleeve 55 toward the sleeve 58, until the parts reach the position shown in Fig. 1. This will return the clutch bar 10 to 90 its former position and disengage the trip pin 44.

As shown in Fig. 11, connecting rods 70 and 71 are connected with the wrist pins 18 and 19 by boxes 72 and 73, which connecting 105 rods serve to rock levers 74 and 75. These levers are pivoted at 76 and 77 on the machine frame, and their forward ends engage slides in reciprocating bars 78 and 79 slidable in guide-ways 80 and 81. On the shaft A is 110 secured a type wheel 82 having flexible type bars 83 cylindrically disposed thereon. The lower end of the slide 79 engages the lowermost type bar when the wheel is arrested, and serves to press it downward. On the 115 shaft B is secured a similar type wheel 84 having type bars 85, the uppermost of which, when the wheel is arrested, is pressed upward by the slide 78. A printing plate inserted between these two opposite type bars 120 will be engaged by them on its opposite sides respectively; and the type on these bars being male and female respectively, will coöperate to produce a raised character in the printing plate.

Having thus described my invention, I 125 claim:

1. The combination of a rotatable driving member, a second rotatable member, an arm carried by the latter member, a connecting 130

member carried by said arm for causing the driving member to engage said arm and operate the second member, a trip device mounted on said arm and organized when advanced to cause the said member to engage the driving member, and means organized to disengage the connecting member at the completion of a single revolution of the driven member and arm, upon the release of 10 the trip device before completion of said revolution.

2. The combination of a rotatable driving member, a second rotatable member, an arm carried by the second member, a connecting member carried by said arm for causing the driving member to engage said arm and operate the second member, a trip device mounted on said arm and organized when advanced to cause the said member to engage the driving member, means being organized to disengage the connecting member at the completion of a single revolution of the driven member and arm, upon the return of the trip device to normal position before 20 completion of said revolution, and means for causing said disengagement of the connecting member at the end of a revolution, upon the trip device being retained in advanced position after said revolution.

3. The combination of a rotatable driving member, a second rotatable member, an arm carried by the latter member, a connecting member carried by said arm, means for causing the connecting member to engage the driving member and cause rotation of the second member and arm, a releasing member movable on a fixed support and arranged to engage the connecting member at one position of its rotation by said arm and disengage it from the driving member, and a trip device carried by said arm and arranged to shift the releasing member to permit the connecting member to engage the driving member.

4. The combination of a rotatable driving member, a second rotatable member, an arm carried by said latter member, a connecting member carried by said arm arranged to cause the driving member to rotate the second member and arm, a releasing member movable on a fixed support and arranged to engage the connecting member at one position of its rotation and disengage it from the driving member, a trip device carried by said arm and arranged to shift the releasing member to permit the connecting member to engage the driving member, the driving member having a clutch face, a rotatable clutch member cooperating with said clutch face, a rotatable shaft on which the clutch member is mounted, means for arresting the latter shaft and clutch member, and means for causing the said arrest of the shaft and clutch member to operate the trip device and cause

the driving member to operate said driven member for a single revolution.

5. The combination of a rotatable driving member, a second rotatable member, an arm carried by the second member, a connecting member pivoted on said arm, means for normally shifting the connecting member to engage the driving member and cause the rotation of the driven member, a releasing member pivoted on a stationary support and arranged to engage the connecting member in 75 one position of its rotation to move it out of engaging position, a trip member pivoted on said arm and arranged to engage the releasing member when the arm and connecting member are in the said position of engagement with the releasing member, to thereby swing the releasing member out of engagement with the connecting member permitting the connecting member to engage the driving member, said releasing member having means tending to retain it in position for engagement with the connecting member, whereby the releasing member after being shifted to disengage the connecting member will return to normal position before the completion of a revolution and will shift the connecting member upon the completion of a revolution to disconnect the driving and driven member.

6. The combination of a rotatable driving member, a second rotatable member, an arm carried by the second member, a connecting member pivoted on said arm, means for normally shifting the connecting member to engage the driving member and cause the rotation of the driven member, a releasing member pivoted on a stationary support and arranged to engage the connecting member in one position of its rotation to move it out of engaging position, a trip member pivoted on 100 said arm and arranged to engage the releasing member when the arm and connecting member are in the said position of engagement with the releasing member, to thereby swing the releasing member out of engagement with the connecting member permitting the connecting member to engage the driving member, said releasing member having means tending to retain it in position for engagement with the connecting member, whereby the releasing member after being shifted to disengage the connecting member will return to normal position before the completion of a revolution and will shift the connecting member upon the completion of a 105 revolution to disconnect the driving and driven member, said trip member being supported for movement axially of the driven members to thereby operate the releasing member, and also supported for movement 120 toward and from said axis, the releasing member having a cam portion arranged to engage the trip member upon the latter being

retained in its releasing position, to thereby prevent the trip member from engaging and shifting the releasing member at the latter part of said revolution.

means for causing an endwise movement of the sleeve on the shaft upon the arrest of said shaft, and means for causing the endwise movement of the clutch member on said sleeve to actuate said operating means 70 and cause said connecting member to operatively connect said driving and driven members.

10. The combination of a rotatable driving member, a rotatable member, means arranged to connect the two members causing the driving member to rotate the second member, an operating member, and means actuated by the operating member organized to cause engagement of the connecting means to produce a single revolution only of the driven member from continued rotation of the driving member, upon the operating means being advanced and retained in such position after the said single revolution, a clutch member on the driving member, a rotatable shaft, a sleeve rotatable on said shaft, a clutch member fast on said sleeve and engaging said clutch member whereby said sleeve is normally rotated, means for arresting the rotation of said shaft, means for causing an endwise movement of the sleeve on the shaft upon the arrest of said shaft, and means for causing the endwise movement of the clutch member on said sleeve to actuate said operating means and cause said connecting member to operatively connect said driving and driven members. 75 80 85 90 95

11. The combination of a rotatable driving member, a rotatable member, means arranged to connect the two members causing the driving member to rotate the second member, an operating member, and means actuated by the operating member organized to cause engagement of the connecting means to produce a single revolution only of the driven member from continued rotation of the driving member, upon the operating means being advanced and retained in such position after the said single revolution, a rotatable shaft, means for arresting the rotation of said shaft, a sleeve loose on said shaft, a clutch member carried by said sleeve, a clutch member on said driving member co-operating with said clutch member, said sleeve having an inclined end face, a corresponding inclined face on said shaft, a spring connecting the said shaft and sleeve arranged to retard co-operation of the inclined faces to advance the sleeve on the shaft endwise, said latter means being arranged to permit endwise movement of the sleeve on the shaft upon arrest of the shaft by said means, and means for causing said endwise movement of the sleeve and clutch member to actuate said operating member to cause connection between the said driving and driven members. 100 105 110 115 120 125

12. The combination of a rotatable driving member, a second rotatable member, an arm 130

- carried by the second member, a connecting member carried by said arm for causing the driving member to engage said arm and operate the second member, a trip device 5 mounted on said arm and organized when advanced to cause the said member to engage the driving member, means being organized to disengage the connecting member at the completion of a single revolution of 10 the driven member and arm, upon the return of the trip device to normal position before completion of said revolution, and means for causing said disengagement of the connecting member at the end of a revolution, upon 15 the trip device being retained in advanced position after said revolution, a clutch member on the driving member, a rotatable shaft, a sleeve rotatable on said shaft, a clutch member fast on said sleeve and engaging 20 said clutch member whereby said shaft is normally rotated, means for arresting the rotation of said shaft, means for causing an endwise movement of the sleeve on the shaft upon the arrest of said shaft, and means for 25 causing the endwise movement of the clutch member on said sleeve to actuate said trip device and cause said connecting member to operatively connect said driving and driven members. 30 13. The combination of a rotatable driving member, a rotatable member, means arranged to connect the two members causing the driving member to rotate the second member, an operating member, and means 35 actuated by the operating member organized to cause engagement of the connecting means to produce a single revolution only of the driven member from continued rotation of the driving member, upon the operating 40 means being advanced and retained in such position after the said single revolution, a clutch member on the driving member, a rotatable shaft, a sleeve rotatable on said shaft, a clutch member fast on said sleeve 45 and engaging said clutch member whereby said sleeve is normally rotated, means for arresting the rotation of said shaft, means for causing an endwise movement of the sleeve on the shaft upon the arrest of said shaft, 50 means for causing the endwise movement of the clutch member on said sleeve to actuate said operating means and cause said connecting member to operatively connect said driving and driven members, and means for 55 returning said sleeve and clutch member to normal position upon release of the arrested shaft. 14. The combination of a rotatable driving member, a rotatable member, means arranged to connect the two members causing the driving member to rotate the second member, an operating member, and means 60 actuated by the operating member organized to cause engagement of the connecting means 65 to produce a single revolution only of the driven member from continued rotation of the driving member, upon the operating means being advanced and retained in such position after the said single revolution, a clutch member on the driving member, a rotatable shaft, a sleeve rotatable on said shaft, a clutch member fast on said sleeve and engaging said clutch member whereby said sleeve is normally rotated, means for causing an endwise movement of the sleeve on the shaft upon the arrest of said shaft, means for causing the endwise movement of the clutch member on said sleeve to actuate said operating means and cause said connecting member to operatively connect said driving and driven members, and a resilient member organized to cause a return of the sleeve and clutch member to normal position upon the release of the arrested shaft. 15. The combination of a rotatable driving member, a rotatable member, means arranged to connect the two members causing the driving member to rotate the second member, an operating member, and means actuated by the operating member organized to cause engagement of the connecting means to produce a single revolution only of the driven member from continued rotation of the driving member, upon the operating means being advanced and retained in such position after the said single revolution, a rotatable shaft, means for arresting the rotation of said shaft, a sleeve loose on said shaft, a clutch member carried by said sleeve, a clutch member on said driving member cooperating with said clutch member, said sleeve having an inclined end face, a corresponding inclined face on said shaft, a spring connecting the said shaft and sleeve arranged to retard co-operation of the inclined faces to advance the sleeve on the shaft endwise, said latter means being arranged to permit endwise movement of the sleeve on the shaft upon arrest of the shaft by said means, means for causing said endwise movement of the sleeve and clutch member to actuate said operating means to cause connection between the said driving and driven members, a second inclined face on said sleeve opposite said inclined face, a similar second inclined face on said shaft arranged to be engaged by said inclined face on the sleeve upon the relative rotation of the sleeve and shaft caused by said spring, whereby the sleeve is returned to normal position. 16. The combination of a rotatable driving member, a second rotatable member, an arm carried by the latter member, a connecting member carried by said arm, means for causing the connecting member to engage the driving member and cause rotation of the second member and arm, a releasing member movable on a fixed support and arranged

to engage the connecting member at one position of its rotation by said arm and disengage it from the driving member, and a trip device carried by said arm and arranged to
5 shift the releasing member to permit the connecting member to engage the driving member, a rotatable shaft, means for arresting the rotation of said shaft, a sleeve loose on said shaft, a clutch member carried by said
10 sleeve, a clutch member on said driving member coöperating with said clutch member, said sleeve having an inclined end face, a corresponding inclined face on said shaft, a spring connecting the said shaft and sleeve
arranged to retard coöperation of the inclined faces to advance the sleeve on the shaft endwise, said latter means being arranged to permit endwise movement of the sleeve on the shaft upon arrest of the shaft by said means, and means for causing said 20 endwise movement of the sleeve and clutch member to actuate said trip device and cause connection between the said driving and driven members.
